APPARATUS FOR ANALYZING A GAS

Philip T. Sprague and Charles A. Sprague,
Michigan City, Ind.

Application June 4, 1937, Serial No. 146,452

6 Claims. (Cl. 23—256)

This application relates to method and means for determining carburetor adjustment, and particularly to method and means of this character involving analysis of exhaust gas to determine the relative percentages of certain constituents thereof by which the operating efficiency of the engine tested may be calculated as a basis for determining the carburetor adjustment necessary in that engine.

It is known that the efficiency of operation of an internal combustion engine depends in part upon the air-fuel ratio governed by the carburetor. It is further known that the composition of the exhaust gas varies in definite relation to the ratio of air-fuel input. Thus, there is a definite relation between such constituents of exhaust gas as CO_2 , CO , H_2 , and O_2 for any given air-fuel ratio supplied by the carburetor. It is therefore possible, by accurate analysis of the percentage or quantity of any two constituents of exhaust gas, to quickly determine whether the air-fuel ratio is too rich or too lean. Such determination is particularly valuable and accurate where the two constituents are determined from the same sample of exhaust gas to avoid possibility of variations in engine operation during the interval between which separate samples are taken.

It is therefore the primary object of this invention to provide means whereby simultaneous determination of the relative percentage of two constituents of a gas may be obtained.

A further object is to provide a novel and simple method of this character requiring only a short time for obtaining the desired result.

A further object is to provide a novel method for rapidly determining whether ignition is taking place in all cylinders of an engine during engine operation.

A further object is to provide novel means for analyzing a gas sample.

A further object is to provide a device of this character having a pair of gas analyzing members arranged for simultaneous operation and connected with means for simultaneously supplying part of the same gas sample to each member, and juxtaposed indicators each controlled by one of said members.

A further object is to provide means of this character by which an exhaust gas sample may be analyzed to simultaneously measure the carbon dioxide constituent and the combined carbon dioxide and oxygen constituents thereof.

A further object is to provide a method of this character wherein the amount of a certain con-

stituent of an exhaust gas is determined by the difference in measurement between the combination of that constituent combined with another constituent, and the other constituent alone.

Other objects will be apparent from the description and the appended claims.

In the drawings:

Fig. 1 is a rear elevation of our improved device in sampling position, with parts shown in section.

Fig. 2 is a rear elevation of our improved device in testing position.

Fig. 3 is a horizontal sectional view of the device taken on line 3—3 of Fig. 1.

Fig. 4 is a front elevational view of the device illustrating the double indicating pointer arrangement.

Fig. 5 is a graph illustrating the accepted relationship between exhaust gas composition and air-fuel ratio.

Fig. 6 is a fragmentary detail sectional view of the gas sampling means.

Fig. 7 is a fragmentary horizontal transverse sectional view illustrating a modified construction of the device with the absorbing units in sampling position.

Fig. 8 is a schematic view of a modified construction of gas analyzing unit in sampling position.

Fig. 9 is a schematic view of the modified gas analyzing unit in absorbing or testing position.

Referring to the drawings, which illustrate the preferred embodiment of our invention, the numeral 10 designates a casing of any suitable size and shape having a sight opening 11 to expose a scale 12 positioned transversely and vertically within casing 10 in rearwardly spaced relation to the front wall of the casing and opposite sight opening 11. Scale 12 includes suitable indicia 13 arranged in arcuate relation thereon to indicate the result of gas analysis in any desired manner, as by volumetric percentage.

Within casing 10 are secured spaced brackets 14, to each of which is pivoted at 15 a gas analyzing unit 16 of the tiltable type as for instance that forming the subject matter of the application of P. T. Sprague et al., Ser. No. 711,982, filed February 19, 1934. As here illustrated, and best shown in cross section in Fig. 1, each of the units may comprise a housing 17 formed of any suitable material and of approximate U-shape providing a gas absorbing chamber 18 containing a gas absorbing agent in one leg, a gas measuring chamber 19 in the other leg, and a chamber 20 between said first named chambers. The device is normally positioned at an angle as illus-

trated in Fig. 1 so that mercury or other inert fluid material or liquid will fill chamber 20 to the level of the bottom of gas measuring chamber 19. A gas intake conduit 21 connects with the chamber 19 adjacent the lower end thereof. A conduit 22 extends from the upper end of chamber 19 to a position above chamber 18; a conduit 23 having a capillary bore branches from conduit 22 and extends into chamber 18 in communication therewith; a conduit 24 branches from conduits 22 and 23 and extends downwardly along the outer side of chamber 18; and a conduit 25 communicates with all the aforementioned conduits opposite conduit 23 and extends upwardly therefrom. Conduits 22, 23 and 24 are preferably rigid, whereas conduits 21 and 25 are preferably flexible, at least in part, for purposes to be hereinafter set forth. Each of these housings 17 is connected to bracket 14 at pivot 15 at substantially the center of said housings. A cup-shaped member 26 open at its upper end is fixedly carried by each housing 17 at the outer side of chamber 18 thereof, and contains a quantity of mercury or other inert fluid. The lower end 25 of conduit 24 extends into cup 26 with its end spaced slightly above the bottom thereof.

The units 16 are interconnected by a link 27 pivoted at its ends at 28 to said units in corresponding or identical relation. A reciprocable rod 29 substantially vertically positioned is pivoted at 30 at its lower end to one side of one unit 16, and its upper end terminates in a head 31 positioned exteriorly of casing 10.

A gas supply conduit 32 of any suitable length extends into casing 10 in any suitable manner from the exterior thereof and connects with the center leg 33 of a T-shaped fitting suitably supported in the upper end of housing 10 by a bracket 34. The aligned cross legs 35 of the T-shaped fitting have the flexible conduits 21 from the respective units 16 connected therewith.

A bracket 36 is secured to the top of casing 10 at the center thereof and carries an arbor 37 on which two pointer arms 38 are pivoted in spaced relation to their upper ends. The pointer arms 38 are positioned adjacent the front wall of casing 10 and terminate adjacent indicia 13 in forwardly spaced relation to scale 12. The upper ends of the pointer arms are pivotally connected 50 to the ends of links 39 extending substantially horizontally and laterally for pivotal connection with the respective upper ends of substantially vertical arms 40 which are carried by a pair of suitable metal bellows or Sylphons 41 mounted 55 on brackets 42 at the side of casing 10. The flexible tube 25 from each unit 16 is connected with one of the Sylphons 41.

To use the device, the units 16 are positioned as illustrated in Fig. 1 by manipulation of rod 29, said units moving together by means of interconnecting link 27 and preferably being provided with suitable means (not shown) for limiting their movement in clockwise direction as viewed in Fig. 1 beyond a tilted or angular position substantially as shown. A gas sample is introduced into supply conduit 32, and passes therethrough to be divided by the T-shaped fitting with which conduit 32 and the corresponding conduits 21 of the two units 16 are connected. The divided gas sample thence enters and fills the gas measuring chamber 19 from which it exhausts through conduits 22 and 24 to atmosphere. Thus portions of the identical gas sample pass to and through each unit 16. The capillary character of bore of conduit 23, together with the fact that the said con-

duit has no exhaust except at its outer end through the conduits from which it branches, substantially prevents absorption of the gas during the time the units are in the sampling position illustrated in Fig. 1.

When a sufficient quantity of the gas has been passed through units 16 to insure exhaust therefrom of gases previously contained thereby, the rod 29 is depressed to pivot the units simultaneously and equally to the absorbing position illustrated in Fig. 2, there preferably being provided suitable stop means (not shown) to limit the pivotal movement of the units in counterclockwise direction as viewed in Fig. 2. When the units 16 are in this absorbing position, the mercury enters and fills chamber 19, thereby closing the conduit 21 of each unit and forcing the gas from the measuring chamber 19 through conduits 22 and 23 to absorption chamber 18. At the same time, the mercury in cup part 26 is shifted to immerse the lower end of conduit 24, whereby both the intake and exhaust ends of the normal gas passage of the device are closed by shifting of the two mercury bodies of each unit. In this way a definite volume of gas is trapped and forced into the absorption chamber 18 whose liquid level has lowered by shifting of the mercury into chamber 19. As the gas absorption occurs, a reduction in pressure results which actuates the respective Sylphons 41 connected thereto by conduits 25 and thereby shifts arms 40 and levers 39 to pivot pointer arms 38 relative to scale 12 whose indicia 13 is calibrated for the units.

In order to achieve the desired result of determining carburetor adjustment from operation of the device it is necessary that the results of the operation of the two units indicate on the scale the percentage of two of the constituents of the exhaust gas. Fig. 5 is a chart showing computed relationships of exhaust gas composition and air-fuel ratio. Thus it will be seen that H_2 and CO decline rapidly to zero as air-fuel ratios increase to 14.7, beyond which point neither occurs; and that O_2 is zero at and below an air-fuel ratio of 14.7 and increases rapidly as air-fuel ratios exceed 14.7. The CH_4 constituent remains substantially constant throughout the whole working range of air-fuel ratios. The CO_2 constituent increases rapidly as air-fuel ratio progresses from its low limit to 14.7, and thereafter declines less rapidly as air-fuel ratio exceeds 14.7. These relationships are based on a fuel composition of C_6H_{12} , water reaction equilibrium constant of 3.8, and formations of 0.15 mol. CH_4 per mol of C_6H_{12} burned.

From the above it will be obvious that it becomes desirable to measure the CO_2 constituent and one of the following constituents H_2 , CO or O_2 . CO_2 is readily absorbed by KOH and hence we prefer to supply one of the units 16 with KOH as an absorbing agent. With CO_2 thus definitely determined, we prefer to use an absorbing agent which will absorb both CO_2 and O_2 substantially as rapidly as KOH absorbs CO_2 , and we have found that the absorbing agent known commercially as "SeezO₂" and forming the subject matter of the patent application of Dorothy Quiggle, Serial No. 35,397, filed August 8, 1935, is most satisfactory for this purpose. Where this absorber is used in the second unit 16, the pointer arms 38 indicate respectively the CO_2 content and the combined CO_2 and O_2 contents, so that the difference in the positions assumed by the two pointer arms constitutes the O_2 constituent. It

will, of course, be obvious that the above absorbing agents, while preferred because of various factors such as substantially similar time required for absorption, rapidity of absorption, and 5 direct absorbing action, may be replaced by any other agents found to serve with equal facility. For instance, pyrogallic acid will absorb both CO₂ and O₂, and may be used if desired; but we find that it lacks both the capacity for and 10 rapidity of absorption present in "SeezO₂".

Using the absorbing agents above mentioned the following results have been obtained. Where air-fuel ratios are below 14.7, the free oxygen content of the exhaust gases will not exceed 0.5 15 if all of the spark plugs are firing; and above 14.7 the oxygen content follows the chart in Fig. 5 when all plugs are firing. It will thus be seen that where the O₂ content is at or below 0.5, the air-fuel ratio is too rich unless a maximum value 20 of CO₂ according to the chart is concurrently obtained; and the approximate air-fuel ratio can be determined from the chart. For instance, with O₂ at or below 0.5 and CO₂ at 12, an air-fuel ratio of about 13.1 is indicated. Likewise, an 25 O₂ content above 0.5 and a CO₂ content above 11 indicates a lean mixture. In this connection it has been found that, if one or more of the spark plugs do not fire, an O₂ content above 0.5 will be obtained, but in no such instance will 30 the CO₂ content exceed 9. Therefore a high O₂ content and low CO₂ content designates failure of ignition in one or more cylinders of the engine. In this way, by the practice of the method as above outlined, it is possible to determine, simultaneously and automatically, factors of 35 exhaust gas condition which accurately indicate the air-fuel ratio supplied by the carburetor and whether and to what extent the same needs adjustment. The reading obtained by this method also immediately shows any failure 40 of ignition and combustion in any cylinder of the engine. To the best of our knowledge, this method and apparatus constitutes a substantial advance in the art by reason of its accuracy, 45 simplicity, rapidity and wide range of derived information.

A slightly modified embodiment of the device has been illustrated in Fig. 7 which has the advantage of compactness. In this construction the units 16 are rigidly mounted, side-by-side on 50 the same shaft 55, which is journaled in brackets 14. The device is similar to the preferred embodiment in all other respects.

While the construction of the absorbing units 55 16 as hereinbefore described is preferred, the same may be slightly altered if desired to reverse the position of gas intake and exhaust as illustrated schematically in Figs. 8 and 9. The parts of this modified analyzer are designated by the same reference numerals as in the preferred form. Thus casing 17 contains chambers 18, 19 and 20 of the same arrangement and purpose as in the preferred embodiment. Conduits 22, 23 and 25 remain the same in construction and arrangement. Gas exhaust conduit 24 is connected with the casing at the lower end of chamber 19, however. Furthermore the external mercury containing chamber 26 is entirely closed and sealed as by a top 50. Conduit 51 branching from conduits 22, 23 and 25 terminates within closed chamber 26 in slightly spaced relation above the bottom of said chamber. Gas supply conduit 21 enters closed chamber 26 and preferably terminates a substantial distance above the chamber bottom to be clear of the contained mer-

cury in all operative positions of the device; and a gas exhaust conduit 52 is positioned opposite conduit 51 terminating at one end in slightly spaced relation above the bottom of chamber 26 and open to atmosphere at its other end. 5

The operation of this modified device is as follows: When the device is in sampling position, Fig. 8, gas from conduit 21 enters chamber 26, whose outlet to atmosphere, conduit 52, is immersed in the contained mercury at its lower 10 end so that the gas passes from said chamber through conduits 51 and 22 to measuring chamber 19 and thence exhausts through conduit 24. Upon tilting of the device to absorbing position, Fig. 8, the mercury in chamber 26 shifts to close 15 conduit 51 and open conduit 52, while the mercury in housing 17 fills chamber 19 and closes exhaust conduit 24. The gas thereby trapped constitutes a sample of known volume which is forced into absorbing chamber 18 by the mercury as in the preferred form of unit. At the same time, gas which continues to enter chamber 26 from conduit 21 is exhausted or shunted to atmosphere through conduit 52. 20

It will be obvious that the apparatus is susceptible of other changes without departing from the spirit of the invention. Thus, for example various types of indicating devices are common in the art and may be employed in place of the siphon-actuated pointers, included among which 30 is the liquid column type of indicator which is obviously readily adaptable to the instant device. 25

We claim:

1. In a gas analyzer, a tiltable unit including a casing containing a gas absorbing agent, a gas 35 measuring chamber, a sealed chamber containing an inert fluid, a gas passage including conduits leading to and from both of said chambers, a by-pass between said passage and casing, means for filling said measuring chamber with inert 40 fluid to transfer gas in said measuring chamber to said casing and seal one conduit communicating with said measuring chamber upon tilting of said unit, said first named fluid sealing one of the conduits entering said sealed chamber upon 45 said tilting, and means for measuring the extent of gas absorption in said casing.

2. In a gas analyzer, a tiltable unit including a casing containing a gas absorbing agent and a pair of sealed chambers, a gas passage including 50 a conduit connecting said chambers and a pair of conduits each communicating with one chamber, a by-pass from said first conduit to said casing, means actuated by gravity upon tilting of said unit to close one of the conduits communicating 55 with each chamber, said means serving to expel gas in at least one chamber into said casing, and means for measuring the extent of gas absorption in said casing.

3. In a gas analyzer, a tiltable unit comprising 60 a casing containing a gas absorbing agent, a gas measuring chamber and a sealed chamber, a gas supply conduit communicating with said sealed chamber, a conduit connecting said chambers and having a by-pass communicating with said casing, an exhaust conduit communicating with the lower end of said measuring chamber, means actuatable by gravity to close said connecting conduit at said sealed chamber and said exhaust conduit and to displace gas from said measuring 70 chamber to said casing upon tilting of said unit, and means for measuring the extent of gas absorption in said casing. 65

4. In a gas analyzer, a tiltable U-shaped housing normally inclined to provide an empty cham- 75

- ber in one leg, the other leg containing a gas absorbing agent, mercury filling the base of the chamber, a sealed chamber carried by said housing and containing a quantity of mercury, a gas supply conduit communicating with said sealed chamber, a conduit connecting the upper end of the empty chamber with the opposite housing leg and with said sealed chamber and terminating above the normal mercury level in the latter, an exhaust conduit extending from the lower end of the upper chamber, the mercury in said housing filling said empty chamber to close said exhaust conduit and force the gas in said chamber into the opposite housing leg and the mercury in said sealed chamber immersing the end of said connecting conduit upon tilting of said unit, and means for measuring the extent of gas absorption following said tilting.
5. The combination with a tiltable gas analyzer having measuring and absorbing chambers connected at top and bottom respectively and separated at the bottom by an inert liquid adapted to enter the measuring chamber to force gas therefrom to said absorbing chamber upon tilting, of a gas supply system comprising a sealed chamber carried by said analyzer and containing
- 10
- 15
- 20
- 25

inert liquid, a gas supply conduit communicating with said sealed chamber, and a conduit branching from said top connection and terminating above the normal liquid level in said sealed chamber, said liquid shifting to seal said last named 5 conduit upon tilting of said analyzer.

6. The combination with a tiltable gas analyzer having measuring and absorbing chambers connected at top and bottom respectively and separated at the bottom by an inert liquid adapted 10 to enter the measuring chamber to force gas therefrom to said absorbing chamber upon tilting of a gas supply system comprising a sealed chamber carried by said analyzer and containing inert liquid, a gas supply conduit communicating 15 with said sealed chamber, a conduit branching from said top connection and terminating in said chamber at one side thereof and above the normal liquid level therein, and a by-pass at the other side of said sealed chamber normally immersed in the liquid at its lower end and open to atmosphere at its opposite end, said liquid shifting to open said by-pass and immerse said branch conduit upon tilting of said analyzer.
